MASSACHUSETTS.

METHOD AND APPARATUS FOR HEATING AND SUPPLYING FEED-WATER TO BOILERS.

1,254,310.

Specification of Letters Patent. Patented Jan. 22, 1918.

Application filed January 23, 1917. Serial No. 144,041.

To all whom it may concern:

Be it known that we, CHARLES W. E. CLARKE and JOSEPH V. SANTRY, citizens of the United States, residing, respectively, at 5 Brookline, in the county of Norfolk and State of Massachusetts, and at Roxbury, in the county of Suffolk and State of Massachusetts, have invented a new and useful Improvement in Methods and Apparatus 10 for Heating and Supplying Feed-Water to Boilers, of which the following is a specification.

The rapid increase in the use of steam turbines and the improved economy which 15 is obtained by operating them at very high steam pressures has resulted in raising very materially the pressures which boiler plants are required to carry. For instance, a pressure of 175 pounds per square inch was re- 20 garded a few years ago as a relatively high boiler pressure, whereas at the present time a pressure of 250 pounds is not uncommon and pressures of even 300 and 350 pounds are contemplated in new plants. This in- 25 crease in steam pressure of course means that the flue gases leaving the boiler must be at a much higher temperature than in the installations designed to operate at lower pressures. The increase in economy 30 derived by operating turbines at high pressures is thus offset to some extent by the increase in the loss of heat in the flue gases. The attempts to reduce this loss by using economizers with these high pressure in- 35 stallations have not been entirely satisfactory due to the fact that the feed water has to be forced through the economizers at a pressure somewhat higher than the boiler pressure, and it appears to be impractical 40 to build economizers capable of withstanding these high pressures.

The present invention aims to devise a method and a system for heating and supplying feed water to boilers which will per- 45 mit the use of economizers in high pressure installations and at the same time will overcome the difficulties heretofore experienced in using apparatus of this character. It is also an object of this invention to devise 50 means for automatically distributing the supply of feed water to the boilers and economizers in accordance with the requirements of the individual boilers.

The manner in which it is proposed to

accomplish these objects will be readily understood from the following description of one embodiment of the invention and the novel features will be pointed out in the appended claims.

The figure of the accompanying drawing 55 shows a system organized in accordance with this invention.

The arrangement shown includes two boilers indicated, respectively, at B and B', each boiler having its own economizer indicated at E and E', respectively. The flue gases from the two boilers pass through their respective economizers and then to the main flue 2. According to the present invention the feed water is pumped into the 60 boilers in two stages, one stage serving to raise the pressure of the water to a pressure as high as it is desirable to carry in the economizers, and the second pump taking the water from the economizers and forcing 65 it into the boilers. In the system shown, the feed water is conducted from the supply through a pipe 4 to a pump 6 which forces the water through a header 8 to the econ- 70 omizers, the branch from the header to the economizer E being indicated at 9, and the branch to the economizer E' being shown at 10. An outlet pipe 11 from the economizer E and a similar outlet 12 from the economizer E' lead the water to another 75 header 14 which conducts the water to a second pump 15. The outlet pipe 16 from this pump delivers the water to boiler inlet 80 pipes 17 and 18, respectively.

The pumps 6 and 15 may be of any suitable 85 type and may be driven in any convenient manner, but preferably they are of the rotary type and are both driven by a suitable motor 20, such as a steam turbine or electric motor. Assuming, for instance, 90 that the normal boiler pressure is 250 pounds, the feed water pressure would normally be about 275 pounds. The first pump 6 may be designed to force the water through the economizers E and E' at a 95 pressure of say 100 pounds; the second pump 15 then takes this water and raises its pressure an additional 175 pounds thus forcing it into the boilers. The difficulty heretofore encountered of subjecting the 100 economizers to boiler pressure thus is avoided. The pressure maintained in the econ- 105 omizers can be made anything that is prac-

tical or desirable but obviously will be made high enough to prevent the water from vaporizing in the economizers.

It is obviously desirable to distribute the water returning to the boilers in accordance with the feed water requirements of the respective boilers. At the same time it is desirable to so distribute the flow of water through the economizers that the economizer for the boiler carrying the heavier load, and consequently receiving the greater supply of flue gases, will be given a greater amount of water to heat than the other economizer. Accordingly the present invention provides a controlling apparatus which accomplishes these objects automatically.

Referring again to the drawings it will be seen that a valve 22 is connected in the outlet pipe 11 from the economizer E and a similar valve 23 is connected in the pipe 12 leading from the economizer E'. Additional valves 24 and 25, respectively, are located in the respective inlet pipes 17 and 25 18 to the boilers B and B'. Each boiler is equipped with an apparatus responsive automatically to changes in the height of the water in the boiler, which is arranged to operate the pair of valves, just described, that 30 control the supply of feed water to it. For this purpose a Copes thermostatic feed water regulator may conveniently be used and accordingly an apparatus of this character is shown. This regulator comprises an 35 inclined expansion tube 28 supported in a triangular frame consisting of a relatively heavy angle iron base 29, a forked upright 30 at one end of this base, and a tension rod 31 forming the other side of the triangle. 40 Two braces 32 and 33 also aid in supporting the expansion tube 28 and prevent it from buckling. The upper end of this tube is connected to the steam space in the boiler and its lower end is connected to a point in 45 the boiler below the lowest water level, while the ends of the tube are located at substantially the maximum and minimum water levels which it is desired to have maintained in the boiler. The lower end of the expansion tube 28 abuts against a bracket fast on the part 29 and the upper end of this tube carries a fitting which bears against the short arm of a bell crank lever 35 that is 50 fulcrumed in the upper forked end of the upright 30. The long arm of this lever 35 of the regulator used with the boiler B is connected by a link 36 with the operating levers of the two valves 22 and 24, while the corresponding arm of the regulator with 55 which the boiler B' is equipped is similarly connected by a link 37 to the valves 23 and 25.

The operation of a feed water regulator of this character is well understood by those skilled in this art. It is merely necessary

here to state that the part of the expansion tube filled with steam is maintained substantially at the temperature of the steam by the liberation of latent heat as the steam condenses due to radiation. On the other hand, the part of the tube filled with water is at some temperature below steam temperature since the radiation of heat from this part of the tube can take place only at the expense of the actual temperature of the water. Consequently, as the water level in the boiler B drops, this level in the tube 28 of the regulator for this boiler also drops and a greater part of the tube thus becomes filled with steam and consequently a larger portion of the tube is maintained at steam temperature. The tube thus expands and lifts the outer end of the lever 35 more or less thus opening the valves 22 and 24 and permitting a greater portion of the feed water to flow into the boiler B. Conversely, when the water level in the boiler B rises, the length of the steam column in the expansion tube 28 will be decreased, thus causing the tube to contract and acting through the connections with the valves 22 and 24 to close them and reduce the flow of feed water to the boiler. The regulator for the boiler B' of course operates in a similar manner; and the water forced through the header 16 by the pump 15 thus is distributed to the two boilers in accordance with their relative feed water requirements. At the same time this arrangement distributes the flow of feed water between the economizers in accordance with the conditions obtaining in the two boilers so that the economizer which is handling the larger volume of flue gases will be given a larger part of the feed water to heat.

While two boilers and two economizers have been shown in the accompanying drawing, it is obvious that the system is equally applicable to a larger number of units. It is also evident that the feature of automatically distributing the feed water between the boilers is applicable to a system in which a single economizer is used for all or several of the boilers instead of a system like that shown in which each boiler has its own individual economizer.

It is obvious that the details of construction of the system, and the character of the elements employed in it will vary somewhat with the requirements of different installations and with the preferences of individual users and that much latitude in making changes of this character is permissible without departing from the spirit or scope of this invention.

What is claimed as new, is:—

1. A system of the character described comprising the combination with a plurality of boilers and an economizer for each of said boilers, of means for forcing feed water

through said economizers at a relatively high pressure, additional means arranged to take the water from said economizers and force it into said boilers, and automatic means constructed and arranged to distribute the flow of water to said boilers and also to said economizers in accordance with the relative feed water requirements of said boilers.

10 2. A system of the character described, comprising the combination with a plurality of boilers, an economizer for each of said boilers and pipe connections for leading feed water to said economizers and from the 15 economizers to the boilers, of a pump for forcing the feed water into the economizers, a second pump for forcing the feed water from the economizers into the boilers, and means responsive to variations in the height 20 of the water in the boilers for controlling both the distribution of water to the economizers and also to the boilers.

3. A system of the character described, comprising the combination with a plurality 25 of boilers, an economizer for each of said boilers and pipe connections for leading feed water to said economizers and from the economizers to the boilers, of a pump for forcing the feed water into the economizers, 30 a second pump for forcing the feed water from the economizers into the boilers, a valve in the outlet of each economizer, another valve in the feed water inlet to each boiler, and an automatic water regulator for 35 each boiler connected to both of said valves for its respective economizer and boiler and operating to close or open them simultaneously as the water in the boiler rises or falls.

40 4. A system of the character described, comprising the combination with a plurality of boilers, an economizer for each of said boilers and pipe connections for leading feed water to said economizers and from the 45 economizers to the boilers, of a pump for forcing the feed water into the economizers, a second pump for forcing the feed water from the economizers into the boilers, valve means controlling the flow of water through

each economizer and to its respective boiler, 50 and thermostatic feed water regulators for said boilers arranged to operate said valve means in accordance with the feed water requirements of the respective boilers.

5. A system of the character described, 55 comprising the combination with a plurality of boilers, an economizer for each of said boilers and pipe connections for leading feed water to said economizers and from the economizers to the boilers, of a rotary pump 60 for forcing the feed water into the economizers, a second rotary pump arranged to force the feed water from the economizers into the boilers, a steam motor arranged to drive both of said pumps, and automatic 65 means responsive to variations in the height of the water in said boilers for controlling the distribution of the water both to the economizers and to the boilers.

6. The method of heating and supplying 70 feed water to a plurality of boilers, which consists in using an economizer with each boiler, pumping the feed water into the economizers at substantially as high pressure as it is desirable to maintain in the economizers, pumping the feed water from the economizers into the boilers at substantially boiler pressure, and automatically distributing the flow of feed water between the economizers and also between the boilers in response to variations in the height of the 75 water in the individual boilers.

7. The method of heating and supplying feed water to a plurality of boilers which 80 consists in using an economizer for each boiler, forcing feed water into the economizers at substantially as high a pressure as it is desirable to maintain in said economizers, forcing the feed water from the economizers into the boilers, and automatically distributing the flow of feed water to the economizers and also to the boilers in accordance with the relative feed water 85 requirements of the boilers.

In testimony whereof we have hereunto 90 signed this specification.

CHARLES W. E. CLARKE.
JOSEPH V. SANTRY.
